UNITED STATES PATENT OFFICE.

WALTER E. SARGENT, OF DETROIT, MICHIGAN.

DIE-SINKING MACHINE.

Application filed October 10, 1918, Serial No. 257,677. Renewed July 11, 1923.

To all whom it may concern:

Be it known that I, WALTER E. SARGENT, a citizen of the United States, and resident of Detroit, in the county of Wayne and State of Michigan, have invented a new and useful Improvement in Die-Sinking Machines, of which the following is a specification.

This invention relates to a machine for sinking or engraving dies for the purpose of reproducing the same from a pattern, either in cameo or intaglio, the said machine being compact, automatic, accurate and expeditious in operation.

One object is to provide a machine of this character which embodies an improved construction of mechanism for causing the engraving tool to traverse a perpendicular surface for the production of dies which include vertical walls in their contour.

Another object consists in providing a machine of this character in which means is included for cutting either right or left hand dies from a single given pattern, by regulating the relative speed of movement of the pattern holder and the tool carrying frame.

A further object consists in providing certain improvements in the form, construction, arrangement and operation of the several parts whereby the above named and other advantages may be effectively attained.

A practical embodiment of my invention is represented in the accompanying drawings, in which

Fig. 1 represents a top plan view of the machine.

Fig. 2 represents a side elevation of the machine, partly broken away.

Fig. 3 represents a rear elevation of the machine, partly broken away.

Fig. 4 represents a detail front elevation of the machine.

Fig. 5 represents a detail vertical section taken substantially in the plane of the line V—V of Fig. 2, looking in the direction of the arrows.

Fig. 6 represents a detail section taken substantially in the plane of the line VI—VI of Fig. 1, looking in the direction of the arrows.

Fig. 7 represents a similar view taken substantially in the plane of the line

VII—VII of Fig. 1, looking in the direction of the arrows.

Fig. 8 represents a detail vertical section taken substantially in the plane of the line VIII—VIII of Fig. 1, looking in the direction of the arrows.

Fig. 9 represents a detail vertical section, partly in elevation, taken substantially in the plane of the IX of Fig. 1, looking in the direction of the arrow.

Figs 10 and 11 represent detail vertical sections, partly in elevation, through the gear case of the main driving mechanism.

Fig. 12 represents a detail horizontal section through the same, and

Fig. 13 represents a detail elevation, partly in section, of the pawl and ratchet mechanism for feeding the tool carrying frame.

The main drive of the machine comes from the motor denoted by 1, (see Fig. 3), the shaft of which carries a gear 2 (see Fig. 12), that meshes with another gear 3 which is fixed upon the end of a shaft 4 horizontally mounted in the main gear case 5, and having a worm 6 thereon. This worm engages a worm gear 7 (see Figs. 3 and 10) which is fixed upon the end of a shaft 8 that is horizontally mounted in the gear case 5 below and at right angles to the shaft 4.

A pair of oppositely facing bevel pinions 9, 10 are loosely mounted upon the shaft 8 and are provided with inwardly extending clutch faces fitted for engagement with complementary faces upon the clutch 11 which is keyed for longitudinal movement upon but against rotary movement upon the shaft 8. From the foregoing description it will be seen that when the clutch 11 is engaged with one of the pinions 9, 10 the said pinion will be rotated with the shaft 8 under the influence of the motor, while the said shaft will turn freely in the other pinion.

These two pinions are continually in mesh with a third pinion 12 that is fixed to a sleeve 13 which is loosely mounted upon the vertical shaft 14; the said shaft being journaled in a bracket 15 that is bolted to the top of the gear case 5. The upper end of the sleeve 13 is fashioned to constitute a clutch face for coaction with a corresponding face on another sleeve 16 that

is keyed for sliding movement upon but against rotary movement upon the shaft 14 (see Fig. 11). This sleeve 16 may be manually operated so as to bring it into and out of engagement with the sleeve 13, and a set screw 17 is provided for temporarily securing the sleeve 16 in the desired position. When the sleeve 16 is clutched to the sleeve 13 the shaft 14 will be rotated through the engagement of the pinion 12 with both of the pinions 9 and 10. A bevel pinion 18 is secured to the upper end of the shaft 14, and it is in constant mesh with a similar pinion 19 (see Fig. 3) which is fixed to a shaft 20 that is mounted in brackets 21, 22 bolted to the end of the main frame of the machine. This frame is indicated by 23, and to it is bolted the main gear case 5 and motor 1, as clearly seen in Figs. 2 and 3.

20 The shaft 20 has a helical gear 24 splined for sliding longitudinal movement thereon but against rotary movement thereon, the key-way in the shaft 20 extending substantially throughout its length. This gear 24

25 mates with a similar gear 25 (see Fig. 8) that is fixed upon a screw 26 which is designed to impart reciprocating movement to the support for the tool carrying frame, as will be hereinafter fully described. At

30 this juncture it may be remarked that the screw 26 will be rotated, through the connection mentioned, by the motor 1, and that its direction of rotation may be reversed by moving the clutch 11 from engagement with

35 one of the pinions 9, 10 into engagement with the other of said pinions.

40 A base 27 is slidably mounted on a bed 28 (see Fig. 3) which has under-cut projections 29 and 30 designed for coaction with the correspondingly formed portions of the base 27. The customary wearing strip 31, with its adjusting screw 32, may be provided intermediate the under-cut projection 30 and the adjacent part of the base 27, if desired.

45 A sleeve 33 (see Fig. 8) is slidably keyed upon the screw 26 which latter is journaled in the bed 28; the said sleeve being rotatably carried in the lower part of the base 27 and fixed against bodily movement therein or therefrom by a collar 34 that is pinned to one end of the said sleeve and a bevel gear 35 which is formed on the other end of the sleeve. A nut 36 is attached to the base 27

50 and threaded upon the screw 26.

From this construction it will be seen that the rotation of the screw 26 will, through the nut 36, impart sliding motion to the base 27 upon the bed 28, and that the direction of this sliding movement of the base will be dependent upon the direction of rotation of the screw 26.

55 The support for the tool carrying frame also includes a stanchion 37 (see Figs. 2 and 8) on the vertical face of which is mounted

a vertically slideable carriage 38. The means of connection between the said carriage and the stanchion 37 consists of two pairs of bolts 39, 39 and 40, 40 which pass horizontally through the stanchion 37 and have T-heads 41, 41 and 42, 42 that are slidably fitted in under-cut slots 43 and 44 (see Fig. 1) fashioned in the carriage 38. An adjusting rod 45 (see Fig. 8) has its lower end swiveled in the base 27, and its intermediate portion threaded into the carriage 38, as clearly shown at 46; so that the rotation of the said rod will serve to move the carriage 38 and its dependent parts vertically toward and away from the base 27.

60 The upper end of the rod 45 is squared for the reception of an ordinary crank to facilitate the manual operation thereof.

65 The carriage 38 acts as the immediate means of support for the tool carrying frame which consists of two main members denoted by 47 and 48 respectively (see Fig. 2). The member 48 consists of an open frame-work as clearly shown in Fig. 1, in which frame-work the spindles 49, 50 of the tracer and cutting tool respectively are mounted in any well known and approved manner. This frame-like member 48 also supports an independent motor 51 which may serve as a means for rotating the tracer and cutting tool, when desired, through the medium of belts 52 and 53, respectively. The member 48 is pivotally secured to the member 47 by oppositely disposed pivots 54 and 55 (see Figs. 1 and 2) while a cap screw 56 passes through the lower portion of the member 48 and is threaded in the member 47 in order to lock the member 48 to the member 47 in any desired adjustment about the pivots 54 and 55. A filler 57 of suitable size 105 and configuration may be employed to occupy the space between the members 47 and 48 immediately below the locking screw 56. Another screw 58 is provided for limiting the downward movement of the member 48 about its pivot, and this screw is threaded in a plate 59 bolted on top of the member 48, while its lower end 60 is adapted to impinge against a bracket 61 which is secured to the front of the carriage 38. A suitable lock nut 62 serves to secure the screw 58 in any desired adjustment. By this arrangement the depth of cut permitted the tool carried by the member 48 may be predetermined.

70 The machine includes mechanism for fulcruming the tool carrying frame as a whole alternately at two different points, both at the same side of, and one below and the other above the face of the pattern, so that the tracer and cutting tool may freely oscillate in compliance with the requirements of the configuration of the pattern and so that a push or pull, as the case may be, is susceptible of being exerted upon the tracer and cutting tool in a direction at an angle 110

above the face of the pattern when a pull is being exerted and in a direction at an angle below the said face when a push is being exerted, in order to cause the tracer and cutter to traverse, and the latter to cut, faces at right angles to the plane of travel of the cutter. This effect is obtained by providing the member 47 of the tool carrying frame with sets of upper and lower pivot pins 63, 63, 64, 64 respectively (see Figs. 1, 2, 5). The points of these pivot pins take into recesses formed in the ends of upper and lower rocking bars 65 and 66 respectively. The bar 66 is mounted upon lower members 67, 67 of the carriage 38, and its mounting is such that it is prevented from moving longitudinally of the said member 67, 67 by flanges 68, 68 which are formed integral with the bar 66 and depend along the outer faces of the members 67, 67; while the bar 66 is permitted to have a certain lateral bodily movement upon the members 67. The upper bar 65 is identical in form with the bar 66 and it is supported in place against upper members 69, 69 of the carriage 38, which members correspond in construction to the members 67, 67. The engagement of the bar 65 with the members 69, 69 is the same in all respects as the engagement of the bar 66 with the members 67, 67.

Mechanism is provided for alternately locking the upper and lower rocking bars 65, 66 against lateral bodily movement so that the tool carrying frame 47, 48 may at one time pivot on the pins 63 and at another time pivot on the pins 64. This mechanism comprises a pair of cone faced clutch members 70, 70 which are mounted for vertical sliding movement in the carriage 38. The said clutch members are bored out in order to permit the passage therethrough of a pair of shafts, 71, 71 which are journaled in the lower and upper members 67, 67 and 69, 69 of the carriage 38. Each of these shafts 71, 71 has a male nut 72, 72 pinned thereto which nuts are designed to mate with female threads formed into the bores of the members 70, 70. It will be seen that, as a result of this arrangement, when the shafts 71, 71 are rotated in one direction the members 70, 70 will be forced automatically into engagement with complementary seats fashioned in the rocking bar 66, as clearly shown in Fig. 5; while the reverse rotation of the shafts 71, 71 will engender opposite movement in the members 70, 70, causing them to be freed from the rocking bar 66 and to be brought into gripping contact with the upper rocking bar 65. When the clutch members are in engagement with the lower bar 66, the tool carrying frame will fulcrum about the pins 64, 64 as its pivot point, and, during the oscillation of the frame about the said pins, the upper rocking bar 65 will have lateral bodily movement

with respect to the members 69, 69 of the carriage 38. When the members 70, 70 are clutched to the upper bar 65, the tool carrying frame will fulcrum about the pins 63, 63 and the lateral bodily movement will be permitted to the lower bar 66.

This motion of the members 70, 70 is automatically accomplished by suitable connections with the source of power already described. This connection is made as follows: A bevel gear 73 (see Fig. 8) is mounted in the base 27 and is fixed to a tube 74 that is keyed for telescopic driving engagement with a solid shaft 75, which is journaled in a boss 76 secured to the carriage 38. Another bevel gear 77 is fixed to the upper end of the shaft 75 and meshes with a corresponding gear 78 that is rotatably mounted upon a transverse shaft 79 (see Figs. 1 and 3) which is mounted in brackets 80, 80 secured to the top of the carriage 38. The gear 78 has a hub 81 from which projects a lug 82 which is fixed to one of the plates 83 of a friction slip-clutch by a bolt 84. One member of this clutch, 85, is splined to the shaft 79, while a coil spring 86 and a compression nut 87 serve to yieldingly hold the clutch plates in frictional engagement through the intervening discs, in the usual manner. A pair of helical gears 88, 88 are keyed to the shaft 79, but have a limited sliding movement thereon through the resiliency of pairs of coil springs 89, 89 which engage opposite sides of the said gears and abut collars 90, 90 fixed to the said shaft 79. These helical gears 88, 88, mesh with corresponding gears 91, 91 that are fixed to the upper ends of the shafts 71, 71.

Hence it will be seen that, as the screw 26 is rotated for the purpose of actuating the tool carrying frame support 27, 37; as already described, the clutch members 70, 70 are simultaneously actuated and that, as the direction of rotation of the screw 26 is periodically reversed for reciprocating the tool carrying frame support 27, 37, the direction of movement of the members 70, 70 is simultaneously reversed. In this connection the parts are so arranged and timed that when the tool carrying frame support 27, 37 starts to move to the right, in Figs. 2 and 8, the members 70, 70 will be brought into clutching engagement with the lower rocking bar 66 so that the tool carrying frame 47, 48 will fulcrum about the pins 64, 64. It should also be remarked that this movement of the members 70, 70 takes place immediately after the screw 26 starts to rotate and that, once the said members have become set in engagement with one of the rocking bars 65, 66, the clutch 82, 83, 85 slips during the remainder of the time the screw 26 is rotated in the same direction. As soon as the direction of rotation of the screw 26 is reversed, the clutch 82, 83, 85 becomes effective to

move the members 70, 70 in the opposite direction until they have clutched the other of the bars 65, 66, after which the said clutch again slips during the continued 5 rotation of the screw 26. Thus it will be understood that the members 70, 70 are automatically caused to alternately engage first one and then the other of the rocking bars 65, 66 as the direction of rotation of the 10 screw is reversed.

The tool carrying frame support 27, 37 is so constructed as to have the capacity of governing the above described mechanism which reciprocates it, and this is accomplished by providing the base 27 with a pair of stops 92 (see Fig. 2) which have T-heads 15 slidably mounted in an under-cut groove 93 formed in the side of the base 27. Each of the said stops takes the form of a thumb 20 nut which is threaded upon the shank of the T-heads, so that the stops may be moved to and clamped in predetermined positions along the groove 93.

The location of these stops is such that 25 they are calculated, during the reciprocation of the base 27, to engage the upper end of a clutch shifting lever 94 pivoted at 95 in a bracket secured to one side of the bed 28. A cross bar 96 (see Fig. 9) is carried in the 30 lower end of the lever 94, the ends of which bar are provided with depending arms 97, 97, that are pinned to a rock shaft 98 which is journaled in bearings 99, 100 secured to the interior of the main machine frame 23 35 adjacent the gear case 5. A drop arm 101 is pinned to the outer end of the shaft 98 and has its lower end connected to a link 102 (see Fig. 2) which latter has its opposite end fixed to an up-standing arm 103 which 40 is secured against rotation on a stub shaft 104 (see Fig. 12) that is mounted in the side of the gear case 5. This stub shaft 104 has its inner end provided with a finger 105 that engages the clutch 11 in the usual 45 manner.

As a result of the construction just described, it will be evident that when the lever 94 is swung in one direction it will throw the clutch 11 into locking relationship with one of the pinions 9, 10, and that when the said lever is thrown in the reverse direction it will cause the clutch 11 to mate with the other said pinions. This alternate swinging movement of the lever 94 is effected 50 by the contact therewith of the stops 92, 92 which periodically engage it as the base 27 reciprocates. By adjusting the stops 92 along the groove 93, so as to vary their separation, the length of stroke of the base 27 55 may be correspondingly varied since the contact of the said stops and the lever 94 controls its reversal.

In order to insure a rapid and clean engagement and disengagement of the clutch 60 11 with and from either one of the pinions 65

9, 10, I provide a spring actuated auxiliary shifter 106 which is pivoted at 107 in a bracket that is bolted to the gear case 5. This auxiliary shifter is normally urged downwardly by a retraction spring 108, and 70 has a bevelled nose which is adapted for co-operation with the similarly formed end of the arm 103. By this arrangement, as the arm 103 is swung in one direction by the link 102, the nose of the shifter 106 will rise 75 up to the apex of the end of the arm 103, and the instant it passes the said apex the spring 108 will impel it to travel rapidly down the opposite inclined surface of said end of the arm 103, thereby assisting in the 80 swinging of the arm 103 so as to rapidly move the clutch 11 from engagement with one of the pinions 9, 10 positively into engagement with the other of said pinions, thereby insuring the regular and continued 85 reciprocation of the base 27.

The bed 28, which has already been referred to as supporting the base 27 and stanchion 37 which constitute the support for the tool carrying frame, is mounted upon 90 the main machine frame 23 for a step-by-step movement in either direction across the top of the frame 23 and along a line of travel transverse to the reciprocating movement of the base 27. For this purpose 95 the bed 28 is mounted on rails 109, 110, 111, which are formed on the upper part of the frame 23, and which are fitted for cooperation with depending ribs 112, 113, 114 on the bed 28; the rib 112 being under-cut to 1 serve the purpose of a gib, and the rib 114 being actually provided with a gib 115. A wearing strip 116 and adjusting screw 117, similar to the parts 31, 32 already described, 1 may be provided on the rib 112.

In order to impart intermittent traveling movement to the bed 28, suitable connection is had with the motor 1. In this regard it will be recalled that the shaft 20 (see Fig. 3) has been described as being 1 constantly rotated by the motor 1, through the bevel gears 18, 19 and the other members of the chain which serve as a connection between the said motor and shaft 20. It will also be understood that the direction of rotation of the shaft 20 will be reversed by the engagement of the stops 92 with the gear shifting lever 94. With these points in mind the immediate means for feeding the bed 28 across the main frame 23 will now be described.

The outer end of the shaft 20 carries a friction clutch (see Figs. 1, 2, 3) which comprises discs 118, 119 which are splined to the said shaft and an intermediate disc 120 which is free for rotary movement on the shaft. Intervening friction facings or discs of leather or like material may be provided in connection with the clutch members 118, 119 and 120 in the usual manner. The

loose member 120 carries a lug 121, in which is pivotally secured, as at 122, one end of a link 123, the other end of which link is pivoted, as at 124, to a rocking arm 125 (see 5 Figs. 2 and 13) that is mounted for oscillation upon the end of the feed screw 126 which is journaled in opposite sides of the main frame 23 and lies below and at right angles to the screw 26.

10 An abutment screw 127 is mounted in a bracket 128 on the side of the frame 23, for the purpose of limiting the rocking movement of the arm 125. Adjustment of the screw 127 will serve to vary the field of 15 movement allotted to the arm 125.

From the construction just described it will appear that when the shaft 20 starts to rotate in one direction it will swing the rock arm 125, through connecting linkage, 20 first in one direction for a short distance and then in the reverse direction for a short distance, as the point 122 at which the link 123 is pivoted to the clutch member 120, 25 121 first rises and then falls in the movement of the said clutch member; and the extent or arc of the rocking motion of the arm 125 will be determined by the adjustment of the screw 127. In order to insure that the clutch 30 may have sufficient power to actuate the arm 125, its spring 129 has a follow-up nut 130 which is threaded on the shaft 20 for suitable adjustment.

After the arm 125 has completed this cycle of movement or oscillation and abuts the 35 screw 127, the continued rotation of the shaft 20 will have no further effect upon it, as the friction clutch 118, 119, 120 will slip. However, as soon as the direction of rotation of the shaft 20 is reversed, the rocking 40 arm 125 will again be actuated so as to execute an oscillation; at the end of which oscillation it will come to rest against the screw 127, while the continued rotation of the shaft 20 in this direction will merely cause 45 the clutch 118, 119, 120 to slip, as already described. This procedure will continue as long as the machine is in operation. Therefore, inasmuch as the direction of rotation of the shaft 20 is controlled by the movement 50 of the base 27, which reverses the said shaft when it reaches the end of each stroke, the rocking arm 125 is rocked once forward and backward for each stroke of the base 27. The purpose of this construction and 55 operation just described is, as already intimated, to feed the bed 28 step by step across the machine transversely to the movement of the base 27, so that the tracer and cutting tool may operate successively upon all portions of the pattern and die to be cut, 60 as will be hereinafter described; and I shall now proceed to set forth the mechanism by which the rocking movement of the arm 125 serves to impart motion to the bed 28.

65 The screw 126 carries on its protruding end, adjacent the arm 125, a ratchet gear 131, the said ratchet being fixed against rotation on the screw. The periphery of the ratchet is provided with a double set of teeth which are oppositely inclined, for 70 alternating engagement with a pawl 132 that is pivotally mounted in the upper end of the rocking arm 125. This pawl is bifurcated to form a pair of points arranged side by side, one of which points lies in the 75 same plane as one set of teeth on the ratchet 131 while the other lies in the same plane as the other set of teeth. Thus the pawl may be swung into operative engagement with either set of teeth on the ratchet 131, 80 in an obvious manner. Each complete cycle of oscillation of the arm 125, which includes one movement in each direction as already described, first pushes the ratchet, 131 through the action of the pawl 132, the distance predetermined by the adjustment of the screw 127 and then retracts the pawl so that it engages a preceding tooth. It will be clear that the direction of rotation thus transmitted to the feed screw 126 will be 85 determined by which set of teeth on the ratchet 131 the pawl 132 engages.

The feed screw 126 is threaded into a nut 133 which is fast to the under side of the bed 28; hence the rotation of the said 90 screw will serve to feed the bed slowly across the main frame 23 in a direction at right angles to the movement of the base 27 upon which is mounted the tool carrying frame. After the screw 126 has fed the bed 95 100 28 to the limit of its movement in one direction, the pawl 132 may be flipped over so as to enter the other set of teeth on the ratchet 131, which will cause the screw 126 to be rotated in the reverse direction by the 105 same mechanism so as to feed it slowly back across the machine.

The work or die to be cut is denoted by 134 (see Figs. 1, 2, 4 and 6) and is mounted upon a duplex support which comprises an 110 upper member 135 and a lower member 136. The member 136 has a central pivot pin 137 which is received in a mounting 138 that is integrally formed at the end of the main frame 23, so that the lower member 136 may 115 be rotatably adjusted about the said pivot pin in a plane parallel to the plane of movement of the base 27 and bed 28. This lower member 136 has its upper face concaved in order to cradle the upper member 135, 120 which construction enables the member 135 to be arcuately adjusted in a plane at right angles to the plane of adjustment of the member 136. A pair of cap screws 139, 139, 125 are threaded into the member 136 and ride in curved slots 140, 140 formed in the mounting 138, in order to fix the member 136 in any desired adjustment; while a pair of cap screws 141, 141, are threaded into the member 135, and ride in slots 142, 130

142 formed in the member 136 in order to secure the member 135 in its desired adjustment. The member 135 has under-cut grooves 143, 143 fashioned in its upper face 5 for the reception of the customary bolts 144, 144, which, together with the usual straps 145, 145 serve to fasten the work 134 in position.

Since the work 134 is fixed in position it 10 will be seen that the combined movement of the reciprocating base 27 and the intermittently fed bed 28 will cause the cutting tool 146 to traverse the entire surface of the die to be cut.

15 The pattern is denoted by 147, and it is mounted on a member 148 which is identical with the member 135. This member 148 is also cradled in a lower member 149 which is identical with the member 136. Cap 20 screws 150, 150, which correspond with the screws 139, 139, are also provided for fixing the member 149 in various adjustments; while similar screws 151, 151 like the screws 141, 141, are supplied for locking the member 148 in the desired adjustment. Bolts 152, 152 and straps 153, 153 which correspond with the bolts 144, 144 and straps 145, 145, act as a means for fastening the pattern 147 to the member 148, which latter is also provided with undercut grooves 154, 154, that are identical with the grooves 143, 143. In order to predetermine the adjustment of the members 135 and 148 in the members 136 and 149 respectively, suitable 30 gages 136* and 149* are provided, as clearly shown in Fig. 4.

Thus it will be seen that the mounting of the pattern corresponds exactly with the mounting of the die save in one particular 40 which resides in the fact that the machine incorporates mechanism for feeding the pattern, if desired, during its operation. To this end the member 149 of the pattern support rests upon a carriage 155, which 45 has depending ribs 156, 157 that ride upon the main frame 23 and engage under-cut rails 158, 159 formed on the top of the latter. A wearing strip 160 and its adjusting screw 161, such as already described, may 50 be used in connection with the rib 157 and rail 159.

55 A nut 162 is fastened to the bottom of the carriage 155 and is threaded on a feed screw 163 that is journaled in the main frame 23 parallel to the feed screw 126. A sprocket gear 164 is rotatably mounted on the protruding end of the screw 163 and lies against a collar 165 that is keyed to the said screw. This collar has a recess which is 60 parallel to its axis and in which is slidably mounted a locking pin 166 which is adapted to be actuated by a thumb nut 167 whereby it may be caused to enter or to be withdrawn from a hole 168 in the sprocket 164. 65 When the pin 166 has its end in the hole

168 the effect will be to lock the sprocket 164 against rotation on the screw 163, in an obvious manner, as clearly shown in Fig. 6.

In order to impart rotation to the screw 163, the sprocket 164 is connected, by means of a chain 169, with another sprocket wheel 170 (see Fig. 2) that is fixed on the end of the screw 126, (see Fig. 5) so as to be driven thereby. In the present instance the sprocket 164 is shown as being one-half the diameter of the sprocket 170 so that the screw 163 will be rotated twice as fast as the screw 126, and hence the pattern 147 will be fed transversely of the machine at a rate 80 of speed just double that of the tool carrying frame; it being understood that the pitch of the threads on the screws 163 and 126 is the same. The effect of this feeding of the pattern in the same direction as and 85 at a speed twice as great as the tool carrying frame will be to engender relative opposite movement between the pattern and the tracer 171 so as to enable a left hand die to be cut from a right hand pattern and vice 90 versa. When it is desired to cut a right from a right or a left from a left, the pin 166 may be disengaged from the sprocket 164 so that the latter will idle upon the screw 163. It will also be understood that 95 the protruding ends of the screws 126 and 163 are squared for the reception of a crank handle in order to permit manual adjustment.

As will be understood by any one familiar 100 with this art, during the operation of the machine the tool carrying frame 47, 48 will oscillate gently about its pivots 63, 63 or 64, 64 according to the direction of travel of the tool carrying frame upon the bed 28, and 105 this oscillation will permit the tracer to follow the undulations existing in the configuration of the pattern, in order that the cutting tool may correspondingly cut the work. It is highly desirable that this action of the 110 tool carrying frame should be gentle and steady; and, to this end, the said frame is counterbalanced by a weight 172 (see Fig. 2) that is connected by means of a strap 173 to a pulley 174 mounted in a bracket 175 115 bolted to the stanchion 37. Another strap extends from the pulley 174 to another pulley 177 which is held in the upper end of the bracket 61; the end of the said strap 176 being bolted to the frame members 48, as indicated at 178.

In view of the fact that the operation of the several elements comprising the machine, has been described in connection with the detailing of their mechanical construction and arrangement, it is not deemed necessary to restate the operation of the machine as a 120 whole, since the same will be easily understood by any operative in this industry.

Attention may, however, be directed to the 13

fact that when the tool carrying frame is moving to the right, in Fig. 2, it is pivoted to fulcrum on the pins 64, 64, and that these pins are located such a considerable distance below the upper surface of the pattern as to be below the mean depth of any figure fashioned therein so that, whenever the tracer encounters a substantially vertical face in the contour of the pattern, a push will be exerted in an upward direction and at an angle of substantially 15 degrees to the plane of movement of the tool carrying frame; which upward push will cause the tracer to easily ride up over the vertical face and enable the cutting tool to cut a corresponding face in the work. When the tool carrying frame is moving to the left, in Fig. 2 it is fulcrumed on the pins 63, 63 and these pins are arranged above the upper face of the pattern, and hence above the mean depth of any figure fashioned therein, so that, when the tracer meets a substantially vertical obstruction in the pattern an upward pull will be exerted on the tracer at an angle of substantially 15 degrees to the plane of travel of the tool carrying frame; this upward pull accomplishing the same result as the upward push just described. By means of the adjusting rod 45 the carriage 38 may be moved so as to hold the tool carrying frame in the proper relationship with respect to the pattern and work to be cut.

The two adjustments provided for the pattern support and work support, which amount to universal adjustments, facilitate the effecting of various angular cuts which the machine is frequently called upon to perform.

When the machine is out of use it may be locked by means of a cotter 179 (see Fig. 5) which is mounted in the top of the carriage 38 and has its lower end fitted to engage a correspondingly shaped recess in the upper rocking bar 65. The cotter 179 is held in its inoperative position by a laterally projecting pin 180 that rests upon the top of the mounting 181 which carries the cotter. This mounting has a channel 182 formed in the bore thereof with which the pin 190 may be brought into coincidence in order to permit the cotter to drop to its interlocking position with respect to the bar 65. As a further step in locking the machine out of operative adjustment the sleeve 16 may be withdrawn from its clutching connection with the sleeve 13 and held in said position by a set screw 17, as already described.

It may be noted that in case it should be desired to eliminate the double pivoting action of the frame 47, 48 and employ the member 48 of the frame as a simple oscillating tool carrying frame, the following procedure may be adopted:

The cotter 179 may be dropped into interlocking position with respect to the bar 65

and the cap screw 56 and filler 57 removed. This arrangement locks the member 47 against movement while it permits the member 48 to oscillate about the pivots 54, 55.

I desire it to be understood that various changes may be resorted to in the form, construction, and arrangement of the several parts without departing from the spirit and scope of my invention, and hence I do not intend to be limited to the details herein shown and described except as they may be included in the claims.

What I claim is:—

1. A machine of the character described comprising, a tool carrying frame, means for supporting said frame, means for carrying said frame supporting means, and mechanism for moving the last named means in one direction and for moving the frame supporting means on its carrying means in another direction.

2. A machine of the character described comprising, a tool carrying frame, stationary means for supporting the work, means for supporting a pattern, and means for moving the pattern support with respect to the frame and the work support.

3. A machine of the character described comprising, a tool carrying frame, means for moving the said frame, stationary means for supporting the work, means for supporting a pattern, and means for moving the pattern support with respect to the frame and work.

4. A machine of the character described comprising, a tool carrying frame, means for moving the said frame, means for supporting a pattern, and means for moving the pattern in the same direction as and at a greater speed than the said frame.

5. A machine of the character described comprising, a tool carrying frame, means for moving the said frame, stationary means for supporting the work, means for supporting a pattern, and means for moving the pattern in the same direction as and at a greater speed than the said frame.

6. A machine of the character described comprising, a tool carrying frame, means for moving the said frame in two directions, means for supporting a pattern, and means for moving the pattern in the same direction as one line of movement of the said frame and at a greater speed than the said last named movement of the frame.

7. A machine of the character described comprising, a tool carrying frame, means for reciprocating the said frame in one direction and for feeding it in another direction, means for supporting a pattern, and means for feeding the pattern support in the same direction as the feed of the said frame and at a greater speed than the feed of the frame.

8. A machine of the character described

- comprising, a tool carrying frame, means for reciprocating the said frame in one direction and for feeding it in another direction, stationary means for supporting a die, 5 means for supporting a pattern, and means for feeding the pattern support in the same direction as the feed of the said frame and at a greater rate of speed than the feed of the frame.
- 10 9. A machine of the character described comprising, an oscillatable tool carrying frame, means for supporting the work and a pattern, and means for fulcruming the frame at two points at one side of the work 75 and pattern.
- 15 10. A machine of the character described comprising, an oscillatable tool carrying frame, means for supporting the work and a pattern, and means for fulcruming the frame at two points one above and one below the mean depth of the figure fashioned in the pattern.
- 20 11. A machine of the character described comprising, an oscillatable tool carrying frame, means for supporting the work and a pattern, and means for fulcruming the frame at two points at one side of the work and pattern, one of said points being above and the other below the mean depth of the 90 figure fashioned in the pattern.
- 25 12. A machine of the character described comprising, an oscillatable tool carrying frame, means for supporting the work and a pattern, and automatic means for fulcruming the frame at two points at one side of the work and pattern.
- 30 13. A machine of the character described comprising, an oscillatable tool carrying frame, means for supporting the work and a pattern, and automatic means for fulcruming the frame at two points one above and one below the mean depth of the figure fashioned in the pattern.
- 35 14. A machine of the character described comprising, an oscillatable tool carrying frame, means for supporting the work and a pattern, and automatic means for fulcruming the frame at two points at one side of the work and pattern, one of said points being above and the other below the mean depth of the figure fashioned in the pattern.
- 40 15. A machine of the character described comprising, an oscillatable tool carrying frame, means for supporting the work and a pattern, and means for alternately fulcruming the frame at two points at one side of the work and pattern.
- 45 16. A machine of the character described comprising, an oscillatable tool carrying frame, means for supporting the work and a pattern, and means for alternately fulcruming the frame at two points at one side of the work and pattern.
- 50 17. A machine of the character described comprising, an oscillatable tool carrying frame, means for supporting the work and a pattern, and means for alternately fulcruming the frame at two points at one side of the work and pattern, one of said points being above and the other below the mean depth of the figure fashioned in the pattern.
- 55 18. A machine of the character described comprising, an oscillatable tool carrying frame, means for supporting the work and a pattern, and automatic means for alternately fulcruming the frame at two points at one side of the work and pattern.
- 60 19. A machine of the character described comprising, an oscillatable tool carrying frame, means for supporting the work and a pattern, and automatic means for alternately fulcruming the frame at two points one above and one below the mean depth of the figure fashioned in the pattern.
- 65 20. A machine of the character described comprising, an oscillatable tool carrying frame, means for supporting the work and a pattern, and automatic means for alternately fulcruming the frame at two points at one side of the work and pattern, one of said points being above and the other below the mean depth of the figure fashioned in the pattern.
- 70 21. A machine of the character described comprising, an oscillatable tool carrying frame, means for supporting the work and a pattern, and means for fulcruming the frame at two points one above and one below the mean depth of the figure fashioned in the pattern, said points being substantially the same distance above and below, respectively, the said mean depth.
- 75 22. A machine of the character described comprising, an oscillatable tool carrying frame, means for supporting the work and a pattern, and means for automatically fulcruming the frame at two points one above and one below the mean depth of the figure fashioned in the pattern, said points being substantially the same distance above and below, respectively, the said mean depth.
- 80 23. A machine of the character described comprising, an oscillatable tool carrying frame, means for supporting the work and a pattern, and means for fulcruming the frame at two points, said last named means comprising a hollow slidable clutch member having its opposite ends fitted to engage different parts of the said frame, and means operating within said member for sliding it in either direction for engaging said frame.
- 85 24. A machine of the character described comprising, an oscillatable tool carrying frame, means for supporting the work and a pattern, and means for fulcruming the frame at two points, said last named means comprising a pair of rocking bars to which the frame is pivoted, a hollow slidable clutch 125
- 90 95 100 105 110 115 120 125 130
17. A machine of the character described

member having its opposite ends fitted to engage said bars, and means operating within said member for sliding it in either direction for locking either of said bars against 5 rocking movement.

25. A machine of the character described comprising, an oscillatable tool carrying frame, means for sliding said frame, means for supporting the work and a pattern, and 10 means for fulcruming the frame at two points, said last named means comprising a slidable clutch member having its opposite ends fitted to engage different parts of the said frame, and means actuated by the means 15 which slides the frame for sliding the said clutch member in either direction for engaging said frame.

26. A machine of the character described comprising, an oscillatable tool carrying 20 frame, means for sliding said frame, means for supporting the work and a pattern, and means for fulcruming the frame at two points, said last named means comprising a pair of rocking bars to which 25 the frame is pivoted, a hollow slidable clutch member having its opposite ends fitted to engage said bars, and means operated within said member and actuated by the means which slides the frame for sliding the said 30 clutch member in either direction for locking either of said bars against rocking movement.

27. A machine of the character described comprising, a tool carrying frame, means 35 for moving the said frame, a support for the work, a support for a pattern, one of said supports being stationary and means for moving the other support with respect to the frame and the stationary support.

40 28. A machine of the character described

comprising, a tool carrying frame, means for moving the said frame, a support for the work, a support for a pattern, and means for moving one of said supports in the same direction as and at a greater speed than the 45 said frame.

29. A machine of the character described comprising, a tool carrying frame, means for moving the said frame, a support for the work, a support for a pattern, one of said 50 supports being stationary, and means for moving the other support in the same direction as and at a greater speed than the said frame.

30. A machine of the character described 55 comprising, a tool carrying frame, means for moving the said frame, a support for the work, a support for a pattern, and means for moving one of said supports in the same direction as the frame and with respect to the 60 frame and the other support.

31. A machine of the character described comprising, an oscillatable tool carrying frame, means for supporting the work and a pattern and means for fulcruming the frame 65 at two points, said last named means comprising a slidable clutch member movable in the same direction as the oscillation of the frame, said clutch member having its opposite ends fitted to engage different parts 70 of the said frame, and means for sliding said clutch member in either direction for engaging said frame.

In testimony, that I claim the foregoing as my invention, I have signed my name this 75 5th day of October, 1918.

WALTER E. SARGENT.

Witness:

JOSEPH E. PACK.
